UNITED STATES PATENT OFFICE.

CHARLES H. ANDERSON, OF CINCINNATI, OHIO.

CAR.

1,175,914.

Specification of Letters Patent. Patented Mar. 21, 1916.

Application filed August 6, 1915. Serial No. 44,069.

To all whom it may concern:

Be it known that I, CHARLES H. ANDERSON, a citizen of the United States, and a resident of Cincinnati, in the county of Hamilton and State of Ohio, have invented certain new and useful Improvements in Cars; and I do hereby declare the following to be a full, clear, and exact description of the invention, such as will enable others skilled in the art to which it appertains to make and use the same.

My invention relates to an improvement in cars and particularly to the roof construction thereof, the object being to provide a roof made up of steel plates so constructed and connected that they will be self supporting, thus doing away with the necessity of separate supporting carline and permitting the roof to be assembled and placed upon the car in a single unit, if so desired.

With these objects in view my invention consists in the parts and combinations of parts as will be more fully described and pointed out in the claims.

In the accompanying drawings, Figure 1 is a view in transverse section showing the roof assembled and in position; Fig. 2 is a view in end elevation of the channeled plates and Fig. 3 is a similar view of latter assembled and secured together.

4 represents the car side posts, which, in the ordinary construction of car, extend clear across the car for supporting the roof. With my construction, the metal posts at 25 each side terminate at 5, and the eaves plates 6, which are substantially the same as those disclosed in Patent 1,148,000 granted to me July 27th, 1915, are secured to the outer faces of the curved upper ends of the 40 posts, and are continued up over the curved ends of the latter and then bent downwardly as at 7, and inwardly as at 8 to form seats or supports extending lengthwise the car for the side edges of the roof.

45 The roof is composed of steel plates 9 each of which is provided adjacent one edge with a pressed channel 10 which latter extends from the seat 7—8, formed in the eaves plate at one side, to the seat formed 50 by the eaves plate at the opposite side of the car, and form strengthening ribs or cross bearers for the roof. The plates 9 are assembled as shown in Fig. 2, with the flat edge 11 of one plate projecting over the 55 channel 10 in the other, and are riveted together at opposite sides of the channel 10 as

shown in Fig. 3. The ends 12 of the plates 9 are cut to project beyond the ends of the channels so as to overlap the upper edges of the eaves plates 6 to which they are secured 60 by the rivets 13. If desired the channels may contain wood fillers 14 to which the trolley boards or other apparatus may be fastened to the roof, the wood forming an anchorage for the screws or bolts. The roof 65 covering may be of cork 15 covered with canvas or other suitable material 16. With this construction the posts of the car extend only to the seats 7 formed by the bends in the eaves plates, instead of entirely across 70 the car, as in the usual construction, the channels in the roof plates forming in effect continuations of said posts. The advantages of this construction of roof are that it does away with the necessity of jointing the 75 plates separately from the roof carline; it makes a neat interior finish, doing away with the necessity of a headlining; the roof will be more easy to cover with cork, and of less weight than any roof construction 80 of the same strength now in use. It can also be assembled as a unit and set into the side posts and eaves plates and secured by riveting as previously explained.

It is evident that many slight changes 85 might be resorted to in the relative arrangement of parts shown and described without departing from the spirit and scope of my invention. Hence I would have it understood that I do not wish to confine myself 90 to the exact construction and arrangement of parts shown and described but,

Having fully described my invention what I claim as new and desire to secure by Letters Patent, is:—

1. In car roof construction, the combination of oppositely disposed side posts bent inwardly at their upper ends and roof plates spanning the space between the ends of the said posts and shoulders to bear against the 100 said ends and also having flanges overlapping the post and secured to the latter.

2. The combination of side posts, eaves plates extending inwardly beyond the upper ends of the side posts and bent to form seats 105 for the roof, and a channeled roof resting on and secured to said seats and also to the eaves plates at the outer sides of said seats.

3. The combination of two series of oppositely disposed side posts, an eaves plate extending inwardly beyond the upper free ends of each series of posts and bent down-

wardly to form seats for the roof, a roof spanning the space between the ends of the two series of side posts and resting on the seats formed by bending the eaves plates and secured to said eaves plates, and a covering for the roof.

4. The combination of side posts, supports secured to said posts and projecting inwardly therefrom in a plane below the top 10 surface of the side posts and a channeled roof secured to said supports.

5. The combination of side posts curved inwardly at their upper ends, eaves plates projecting inwardly over said curved ends 16 and bent downwardly to form seats and a channeled roof secured to said seats, the side edges of the roof intermediate the channels projecting over the upper ends of the side posts.

6. The combination of side posts curved inwardly at their upper ends, roof support-

ing seats carried by the posts at the upper ends of the latter and a roof composed of metal plates each having a channel closed by the next adjacent plates, the said plates 25 being riveted together, and the roof as a whole riveted to the seats on the post.

7. The combination of side posts curved at their upper ends, roof supporting seats projecting from the upper ends of the posts, 30 and a metal roof composed of plates riveted together, each plate having a channel with a wood filler therein, the channels extending transversely of the roof.

In testimony whereof, I have signed this 35 specification in the presence of two subscribing witnesses.

CHARLES H. ANDERSON.
